Patented May 24, 1927.

UNITED STATES PATENT OFFICE.

GEORGE STANFORD WITHAM, JR., OF HUDSON FALLS, NEW YORK.

FOURDRINIER MACHINE AND PROCESS OF PAPER MAKING.

Application filed September 8, 1926. Serial No. 134,284.

My invention relates to Fourdrinier machines, and particularly to improvements designed to eliminate the use of deckle straps in machines of the present type. It also relates to a new method or process of paper making whereby a web is formed over the full width of the wire.

The present types of Fourdrinier machines are provided with what are known in the art as "deckle straps," consisting of endless belts of soft rubber lying upon and near the edges of the wire, and there forming lateral dams preventing the pulp fibres from being carried over the edges of the wire before they are sufficiently felted or intermeshed to form a unitary web. These straps run over flanged pulleys, and the lower strands thereof are supported upon and carried by the moving wire. They usually extend in contact with the wire from the pond to the third suction box and regulate, and necessarily limit, the width of the web which can be formed. The straps are of comparatively large cross section, to provide dams of the proper height, and must be replaced from time to time at considerable expense and inconvenience.

Various schemes for the elimination of deckle straps have been recently proposed, including the substitution therefor of stationary plates having thin, flexible sheets of rubber in contact with the wire, and the substitution of air or water jets, either with or without a stationary plate, to form dams for holding the stock on the wire.

My invention, in its broadest aspects, contemplates the elimination of all forms of edge rulers or deckle straps, and involves a new method of procedure whereby the full width of the wire is utilized without attendant loss of stock, and an improved product is produced by reason of a better hydration of a portion of the stock incorporated therein.

The objects of my invention, therefore, are to provide a process of paper making which will eliminate all forms of deckle straps or their equivalents, which will permit the utilization of the full width of wire in a Fourdrinier, which will result in an improved product, and which may be performed without loss of stock.

Another object of my invention is to provide means whereby the present type of Fourdrinier may be adapted to produce paper according to my process without sub-

stantial modification in design, and at comparatively small expense.

My invention, therefore, includes the hereinafter described process and the novel elements and combinations of elements illustrated in a more or less typical form in the accompanying drawing, and described below.

In the drawing—

Fig. 1 is a longitudinal section of the wet end of a Fourdrinier illustrating, on a small scale, the general features of my invention;

Fig. 2 is a fragmentary section of Fig. 4 in the plane 2—2;

Fig. 3 is a side elevation or section on the line 3—3 of the fragmentary portion shown in Fig. 2; and

Fig. 4 is an enlarged fragmentary plan view of a portion of the machine showing the application of my device.

In considering the drawings, it will be apparent that only one side of the machine is shown, but it is to be understood that the details of the opposite side are substantially identical with those illustrated.

Referring to the drawings, 1 is the breast roll, and 2, the rolls which carry the wire, 3, all of which are in the usual well known form. 4 represents the slice; 5, the slice box; 6, the head box; and 7, the screens.

Referring more particularly to Fig. 1, 8 represents the wire pit which acts as a save-all and which is drained through piping, 9, to the mixing pump, 10. The pump, 10, is also connected to the stock regulator through piping, 11, and serves to intermix the stock drained from the wire pit or save-all, 8, with stock from the regulator and force the mixture to the screens, 7, through piping, 12, and valve, 13. 14 represents the tank into which the white water from the suction boxes and couch rolls is drained, and from which it is drawn by pump, 15, and reconveyed to the beaters and a save-all.

In its broadest aspects, my invention contemplates permitting the stock to flow unrestrictedly over the edges of the wire, as illustrated by the arrows, 16, in Figs. 1 and 2, and thereafter reconveying the overflow to the slice box. This, of course, may be done in various ways and by various means, but I prefer to collect the overflow of highly diluted stock in a save-all, such as a closed wire pit, and use it as a dilutent for the mixture issuing from the stock regulator, and to so adjust the flow from the regulator that

the resulting mixture issuing from pump, 10, is of the proper consistency for delivery to the screens.

Referring particularly to Figs. 2, 3 and 4, which represent in a more or less typical manner the relative positions of the various elements at the wet end of the present type of Fourdrinier, it will be apparent that the stock stream flowing over the edge of wire, 3, at any considerable velocity may be carried beyond the edge of the wire pit, 8, and flow on to the floor, 18. Moreover, pulp and water flowing over the edges of the wire may be thrown about and into the bearings, 19, of the table rolls. This clearly may be obviated by increasing the width of the wire pit and increasing the length of the table roll shafts, 20, as may be required. However such changes in the construction of the machine itself are quite unnecessary as very good results are obtained by the interposition of plates or other means for deflecting the material flowing over the edges of the wire to the wire pit.

Supported upon the rail, 21, by the elements, 22, is the upper deflecting plate, 23, which extends vertically somewhat above the plane of the upper wire strand, 3, and somewhat below the shafts, 20, of the table rolls, 2, to provide a protection for the bearings, 19. This upper deflecting plate is spaced horizontally from the edge of the wire, 3, and this spacing may be varied by adjusting the binding nuts, 26, which coat with studs, 27, in the rail. Where used, this deflecting plate and the next lower deflecting plate, 28, should extend from a point near the slice and in a direction about parallel to the edge of the wire until they reach a point along the wire where the pulp fibers begin to felt or intermesh and cease to be carried over the edges of the wire. In many cases, ten feet is sufficient.

To prevent pulp from being deflected or re-deflected from the upper deflecting plate to the lower strand of wire, 3, where it would soon cause ridges to form and result in breakage, a lower deflecting plate, 28, is provided. The upper edge of this plate is somewhat within or behind a vertical plane passing through the outer edge of the upper strand of wire, and the lower edge is somewhat outside or in front of such a plane passing through the outer edge of the lower strand of the wire. In cross section, this plate may be in any form which will satisfactorily perform the function for which it is intended. Where necessary, a third, and still lower plate, 29, may be provided to insure that all the stock will be deflected to the wire pit.

Where the lateral flow of the stock stream just after it strikes the wire, 3, is wholly unrestricted, the resulting web, at the edges and for a substantial distance inwardly

therefrom, is thinner than at the center which necessitates cutting this portion from the web. For the purpose of reducing the width or extent of this thinner portion, it is advantageous to use the adjustable wing plates, 40, which extend a short distance, say 10 or 12 inches, from the point where the stock stream first strikes the wire, and the bottom edges of which are just above and out of contact with the wire. These wing plates do not form a tight seal with the wire, but nevertheless serve to momentarily restrain the lateral flow of the stock thereon. They tend to cause the formation of small pools in the issuing stock stream on each side of the wire from which the water is quickly dropped and from which the fibers are deposited near the edges of the wire in a layer approximating the required standard thickness of the web at points remote from the edges of the wire. These plates may be hinged, as shown at 30, and adjusting means comprising binding nuts, 31, and slotted elements, 32, may be provided whereby the angle of splay of the wing plates and the splay of the issuing stock stream may be varied, as shown at 29'.

To further regulate and control the width of the stock stream as it issues from the slice, I provide, preferably within the slice box, 5, the adjustable slice plates, 33, which may be moved towards or from the center of the slice, as shown at 33', to narrow or widen the slice opening as may be desirable under the particular conditions affecting the operation. These adjustable slice plates may be secured in position by the binding nuts, 34, coacting with studs, 35, passing through the slotted openings, 36, in elements, 37. The plates, 33, are also provided with an angular portion, 38, adapted to slide within a recess, 39, in the side of the slice box so that the flow from the slice is substantially limited to the opening included between the plates, 33, at the opposite sides of the machine.

Referring to Fig. 1, it will be apparent that there is shown a save-all, 41, which is not shown in the other drawings, and which serves to protect the lower strand of the wire near the breast roll 1. Where the portion of this save-all which extends beyond the wire and communicates with the wire pit forms a protection for the lower strand of the wire, the plate, 29, may stop.

It should be evident from the foregoing that many of the details and elements of my device which I have described, while of great value in obtaining the most satisfactory operation and results, are not absolutely essential, and it should also be borne in mind that the mechanical features are designed and illustrated for and as applied to one present type of Fourdrinier. It should also be apparent that in its broad aspects,

no particular form of apparatus is necessary to attain the beneficial results flowing from the utilization of the full width of wire and according to the procedure which I have described above.

5 It is therefore to be understood that the words which I have used in describing my invention are words of description rather than words of limitation, and that changes 10 within the purview of the appended claims may be made without departing from the true scope and spirit of this invention.

What I claim is—

1. In a Fourdrinier machine, the combination with a wire, of means spaced above 15 but in close proximity to the upper surface thereof for momentarily restraining the lateral flow of stock after it strikes said wire.

2. In a Fourdrinier machine, the combination with a wire, of means for varying 20 the splay angle of the stock stream after it strikes the wire.

3. In a Fourdrinier machine, the combination with a wire, of means for momentarily restraining the lateral spread of the 25 stock stream after it flows upon the wire, and means for varying the degree of restraint.

4. In a Fourdrinier machine, the combination with a wire of a plate laterally spaced 30 from and beyond the edge of said wire, and adapted to limit the distance that stock will be projected from the wire.

5. The combination set forth in claim 4, 35 together with means for adjusting the spacing of said wire and plate.

6. In a Fourdrinier machine, the combination with a slice and wire, of means for regulating the width of the stock stream 40 issuing beneath the slice, and means laterally spaced from the edge and beyond said wire adapted to limit the distance that stock will be projected beyond said wire.

7. In a Fourdrinier machine of the character described, the combination with means 45 for varying the width of the stock stream issuing upon the wire, of means beyond the apron for momentarily restraining the otherwise substantially free, lateral flow of said stream on the wire.

8. In a Fourdrinier machine, the combination with means for varying the width of the stock stream issuing upon the wire, of means for varying the splay angle of the stream after it strikes the wire.

9. A Fourdrinier machine having a plate 50 extending longitudinally between the upper and lower strands of the wire adapted to deflect stock flowing over the upper edge of said wire from the bottom strand thereof.

10. In a Fourdrinier machine, the combination with a wire and slice, of means for momentarily restraining the lateral flow of stock on the wire as it issues from beneath 55 the slice, and means for directing the over-

flow from said wire from the lower strand thereof.

11. In a Fourdrinier machine, the combination with a wire and slice, of means for varying the width of the stock stream issuing 70 from beneath the slice, and means for directing the overflow from said wire from the lower strand thereof.

12. In a Fourdrinier machine, the combination with a wire and slice, of means for varying the width of the stock stream issuing 75 from beneath the slice, means for momentarily restricting the lateral flow of said stream on the wire, and means for directing the overflow from said wire from the lower 80 strand thereof.

13. In a Fourdrinier machine, the combination with a wire and slice of means for varying the splay of the stock stream issuing 85 from the slice, and means for preventing the overflow of stock from the wire from being deposited on the lower strand thereof.

14. In a Fourdrinier machine, the combination with a wire and slice, of means for 90 varying the width of the stock stream issuing from beneath the slice, means for varying the splay of the stream as it issues, and means for protecting the lower strand of the wire from stock overflowing the upper 95 strand.

15. In a Fourdrinier machine adapted to form a web the full width of the wire, the combination with means for deflecting the overflow of stock from the wire to a separate save-all, of means for returning said stock to the slice box.

16. In a Fourdrinier machine adapted to form a web the full width of the wire, the combination with means for deflecting the overflow of stock from the wire to a separate save-all, of means for mixing the contents of the save-all with stock from the regulator and returning the mixture to the screens.

17. In a Fourdrinier machine adapted to form a web the full width of the wire, a plurality of plates extending longitudinally of the wire and adapted to deflect material overflowing the wire to a save-all.

18. In a Fourdrinier machine adapted to form a web the full width of the wire, wing plates adjacent the slice and extending longitudinally of and in close proximity to the upper surface of the wire for a comparatively short distance, whereby the lateral flow of the stock on the wire is momentarily restrained.

19. In a Fourdrinier machine adapted to form a web the full width of the wire, the combination with means adapted to intercept the overflow from the wire, of means for returning said overflow to the stock supply.

20. In a Fourdrinier machine, the com-

bination with a slice and wire, of means for regulating the width of the stock stream as it issues upon the wire, means for intercepting the overflow of stock from said wire, and means for returning the intercepted flow to the stock stream.

21. In a Fourdrinier machine adapted to form a web the full width of the wire, the combination with a slice and wire, of means for regulating the width of the stock stream issuing upon the wire, means for intercepting the overflow of stock from said wire, and means for returning the intercepted flow to the stock stream, including means for mixing the intercepted flow with stock from the regulator.

22. In a Fourdrinier machine adapted to form a web the full width of the wire, the combination with a slice and wire, of means for regulating the width of the stock stream issuing upon the wire, means for momentarily restraining the lateral flow of the issuing stock on the wire, means for intercepting the overflow from the wire, and means for returning the intercepted flow to the stock stream.

23. In a Fourdrinier machine adapted to form a web the full width of the wire, the combination with a slice and wire of means for regulating the width of the stock stream issuing upon the wire, means for momentarily restraining the lateral flow of the issuing stock, means for intercepting the overflow from the wire, and means for returning the intercepted flow to the stock stream, including means for intermixing the intercepted flow with stock from the regulator.

40 24. In a Fourdrinier machine adapted to form a web the full width of the wire, the combination with a slice and wire, of means for momentarily restraining the lateral flow of stock on the wire as it issues from the slice, means for intercepting the overflow from the wire, and means for returning the 45 intercepted flow to the stock stream.

25. In a Fourdrinier machine adapted to form a web the full width of the wire, the combination with a slice and wire, of means for momentarily restraining the lateral flow of stock on the wire as it issues from the 50 slice, means for intercepting the overflow from the wire, and means for returning the intercepted flow to the stock stream intermixed with stock from the regulator.

26. The process of forming a web the full width of the wire in a Fourdrinier machine, which comprises permitting the stock stream to flow unrestrictedly over the edges of the wire, and intercepting and returning the overflow to the stock stream. 55 60

27. The process of forming a web the full width of the wire on a Fourdrinier machine, which comprises flowing a stream of stock on said wire of a width less than the wire itself, momentarily restraining the lateral flow of said stock and thereafter permitting an unrestricted lateral flow over the edges of said wire, and returning the overflow to the stock stream. 65

28. The process of forming a web the full width of the wire on a Fourdrinier machine, which comprises flowing a stream of stock on said wire of a less width than the wire itself, momentarily restraining the lateral flow of said stock and thereafter permitting an unrestricted flow over the edges of the wire, intermixing the overflow with new stock to form a properly diluted mixture, and returning the mixture to the stock stream. 70 75 80

29. The process of forming a web the full width of the wire on a Fourdrinier machine, which comprises flowing a stream of stock on said wire and permitting said stream to flow substantially unrestrictedly over the edges of the wire intermixing the overflow with new stock to form a properly diluted mixture, and introducing the mixture in the stock stream.

GEORGE STANFORD WITHAM, JR.
